DESIGN FOR AN AUTOMOBILE FENDER

Robert Cadwallader, Detroit, Mich., assignor to
Chrysler Corporation, Highland Park, Mich., a
corporation of Delaware

Application March 31, 1939, Serial No. 83,958

Term of patent 7 years

To all whom it may concern:

Be it known that I, Robert Cadwallader, a citizen of the United States, residing at 17580 Pennington Drive, in the city of Detroit, county of Wayne, and State of Michigan, have invented a new, original, and ornamental Design for Automobile Fenders, of which the following is a specification, reference being had to the accompanying drawing, forming part thereof, in which:

Fig. 1 is a top plan view of an automobile fender showing my new design.

Fig. 2 is a side elevation of the fender shown in Fig. 1.

Fig. 3 is a front end view of the fender shown in Fig. 1.

I claim:

The ornamental design for an automobile fender, substantially as shown.

ROBERT CADWALLADER.
